UNITED STATES PATENT OFFICE.

LEO HOLUB, OF HARTSHORNE, OKLAHOMA.

GUNSTOCK.

Application filed January 24, 1924. Serial No. 688,228.

To all whom it may concern:

Be it known that I, LEO HOLUB, citizen of the United States, residing at Harts-
5 horne, in the county of Pittsburg and State of Oklahoma, have invented certain new and useful Improvements in Gunstocks, of which the following is a specification.

This invention relates to improvements in gunstocks and method of making the same. 10 An object of the invention resides in constructing a gun stock of metal which is adapted to replace the use of wood, the supplies of which are being rapidly exhausted.

15 Another object of the invention is to provide a cast metallic gun stock formed with a hollow butt portion, the size of the recess of which may be varied in order to change a balance in a gun to which the stock is applied.

Another object of the invention is to provide a gun stock which is cast in a single piece and in which the butt portion and part of the grip portion are cast in a substantially finished condition, while the forward end of the grip portion is cast with a considerable amount of extra material which is removed at the time of applying the stock to a particular gun breech so that the same 25 may be ground or milled to accurately fit the gun breech to which it is applied, as the sizes of gun breeches of the same type vary in each particular breech.

A further object of the invention resides 30 in providing a simple method of making a gun breech by casting an aluminum stock in which the butt portion and part of the grip portion are in a substantially finished condition leaving the free end portion of the grip 35 with surplus material adapted for removal at the time of fitting the stock to a gun breech in order to provide an accurate fit between each gun stock and its corresponding breech, after which the stock may be polished to provide a finished surface on the exterior thereof.

The invention includes other objects and improvements in the details of construction and method of making the gun stock which 40 are clearly pointed out in the following detailed description and in the claims directed to the preferred form of the invention, it being understood, however, that slight variations may be made within the scope of this 45 description and the appended claims.

In the drawings forming a part of this application,

Figure 1 is a view in side elevation of the improved gun stock.

Figure 2 is a view partly in section showing how the butt end of the stock is formed with a recess.

The gun stock forming the subject of this invention is preferably cast in one piece from aluminum or of similar material having the quality of being light, of producing strength, and capable of being cast with a finished exterior surface, or such surface that it is not necessary to machine or grind the exterior thereof in order to provide a surface ready for polishing where it is desired to produce a highly polished exterior surface.

The gun stock is indicated generally at 1, including a grip portion 2, merging at 3 into the butt portion 14 which is tapered in the usual manner from the juncture 3 to the end 5 which is formed with a recess 6 extending through the major portion of the butt, the depth of which is determined and varied in different stocks according to the balance which is to be produced in the gun for which the stock is made. A butt plate 7 is secured at its end portion to the end of the butt 5 by screws or the like 8, entirely covering and enclosing the recess 6 which if desired, may be used for housing cleaning or other accessories adapted for use in connection with the gun. The major portion of the stock including the butt 4 and the adjacent portion of the grip 2 are cast preferably as above stated, in a manner that the exterior surface is produced in a substantially finished condition in the casting operation. The recess 6 is also formed in the casting during this casting operation in a well known manner and it is to be understood that it may be drilled deeper into the butt portion after or at the time that it is applied to the breech of a gun for changing the balance as desired. The free end of the grip portion 2 is cast with an excess of material as shown in the drawing, the finished dimension of the stock being indicated by dotted lines at 9, so that the end of the stock is adapted for machining, milling, or grinding at the time of fitting it to a particular gun breech in order that an accurate fit may be made between a particular stock and a particular gun breech. This is necessary, because the dimensions of gun breeches

100
105
110

vary slightly, due to inaccuracies in the casting and machining thereof as well as variations which would occur in casting the gun stock, it being merely necessary however, to provide additional material for the part of the grip which actually receives the gun breech, the remaining portion of the stock being made in a finished condition.

It will therefore be clear that a manufacturer may make gun stocks as above described and sell the same to the manufacturers of guns and breech mountings who finish the end portions as indicated at 9 at the time of actually selecting a particular gun stock for a particular gun breech. A better fit and a more substantial structure is obtained in this way as the end of the gun stock can not only be machined or ground to fit the gun breech but the same may be drilled and threaded for receiving the fastening screws to secure the breech to the stock at the same time.

After the casting of the gun stock 1, the end plates 7 are applied as above described immediately after the casting operation and before the stock is ready for delivery to be fitted with a particular gun breech.

What is claimed is:

1. A method of making gun stocks consisting in casting a gun stock of metal having the butt portion and a part of the grip

portion in a substantially finished condition, applying a butt plate to the end of the butt portion of the stock, and providing the end of the grip portion with surplus material adapted for removal in fitting the stock with a gun breech whereby an accurate fit may be obtained.

2. A method of making gun stocks consisting in casting a stock in one piece of metal having a finished outer surface, the butt portion being cast with a recess extending throughout the major portion thereof, and the free end of the grip portion being provided with surplus material adapted for subsequent removal to provide an accurate fit with a gun breech, and applying a butt plate to the end of the butt portion of the stock to form a closure for said recess.

3. As an article of manufacture, a gun stock comprising an integral metallic casting formed with a partially finished grip portion merging into a finished hollow butt, the end of the grip portion being provided with surplus material adapted for removal in finishing said grip portion to accurately receive and fit the breech portion of a gun to which it is applied, and a butt plate secured to the end of the butt portion.

In testimony whereof I affix my signature.

LEO HOLUB.
